UNITED STATES PATENT OFFICE.

NATHANIEL JUDSON, OF NEW YORK, N. Y.

DESIGN FOR A STOCKING.

Application filed June 6, 1927. Serial No. 22,348. Term of patent 14 years.

To all whom it may concern:

Be it known that I, NATHANIEL JUDSON, a citizen of the United States, and a resident of the city of New York, borough of Manhattan, in the county and State of New York, have invented a new, original, and ornamental Design for a Stocking, of which the following is a specification, reference being had to the accompanying drawing, forming part thereof.

The figure is a rear perspective view of a stocking showing my new design in which the lining emphasizes the design and does not represent specific color, the sole of the stocking being represented by a demarcating line.

I claim:

The ornamental design for a stocking, substantially as shown and described.

NATHANIEL JUDSON.
